UNITED STATES PATENT OFFICE.

WILLIAM H. SLATTEN, OF CHICAGO, ILLINOIS.

CAR-ROOF.

1,203,148.

Specification of Letters Patent. Patented Oct. 31, 1916.

Application filed April 3, 1916. Serial No. 88,438.

To all whom it may concern:

Be it known that I, WILLIAM H. SLATTEN, a citizen of the United States of America, and a resident of Chicago, in the county of Cook, State of Illinois, have invented certain new and useful Improvements in Car-Roofs, of which the following is a specification.

This invention relates to that type of car roofs, which form the subject matter of Letters Patent No. 1,149,093, issued August 3, 1915, to Slatten and Nolan for car roof construction.

The present improvement has for its object to provide a simple and efficient structural formation and association of parts, whereby the interlocking and clamping connections of certain roof elements are attained in a manner to permit of the usual limited flexibility required in actual use, and with an absence of openings from the exterior to the interior, all as will hereinafter more fully appear.

In the accompanying drawings:—Figure 1 is a fragmentary perspective view of a roof construction embodying the present improvement, parts of the structure being broken away and shown in section to more clearly show details of construction. Fig. 2 is an enlarged detail longitudinal section on line $x-x$, Fig. 1. Fig. 3, is a similar view on line $x'-x'$, Fig. 1.

Similar reference numerals indicate like parts in the several views.

As represented in the drawings, the car roof frame comprises the usual side plates or pieces 1 with their fascia boards 4, ridge pole or piece 5, purlins 6, carlines 7, and wood sheathing boards 8, of the conventional construction and arrangement.

9 designates a plurality of transversely disposed roofing sheets of metal formed with marginal rebent flanges 10, constituting elements of the standing seams of the metal roof covering of the car, and each of said seams will comprise in addition to said flanges 10, a transversely arranged channel plate 11, the upturned flanges or side webs of which have interlocking engagement with the roofing sheet flanges 10, and a cap piece or member 12 seated upon said parts and covering and inclosing the same as shown.

13 designates the running board, supported centrally above the roof by the usual saddle blocks 14, and in the construction shown said saddle blocks 14 have bearing in the

valleys of the channel plates 11 of the roof covering and are in turn connected to the running board 13 by intermediate saddle plates 15 secured to the undersurface of the running board and having depending transverse flanges or webs forming receiving channels for the upper portions of the saddle blocks 14 as shown.

The construction so far described, is the same as that shown and described in the aforesaid Slatten and Nolan Patent No. 1,149,093, and in connection with substantially the same structure, the present invention involves a detail formation and association of parts whereby the saddle blocks 14 and saddle plates 15, as well as the channel plates 11, are secured in place in a substantial manner which admits of limited flexibility, and with an absence of openings through the roof structure such detail structure comprising as follows:

16 designates a confining piece formed of plate metal and consisting of a central main portion 17, a pair of upstanding V shape portions 18 and end extensions 19 which are aligned with the main portion 17 and are provided with orifices for the passage of attaching bolts or screws 20 as shown. In one part of this invention the confining plates 16 fit snugly over an outer portion of a channel plate 11 with the fastening screws aforesaid passing through the orifices in the end extensions 19 and screwing vertically into a side piece or plate 1 of the roof frame to secure said channel plate 11 in place in a substantial and convenient manner.

In another part of the present invention the central main portion 17 of the confining piece 16 is formed with an upwardly deflected portion 21 providing a receiving recess adapted to contain the head or nut of a vertically disposed bolt 22, the shank portion of which passes through an orifice formed therefor in said upwardly deflected portion 21. The bolt 22 extends vertically through the saddle block 14 and through the saddle plate 15 with its nut or head having bearing upon said saddle plate as shown. The described arrangement is adapted to provide a conveniently applied connection, flexible in a horizontal plane, between the running board 13 and the roof frame and parts of a car, similar to that described in the aforesaid Slatten and Nolan Patent No. 1,149,093. In the preferred construction shown the confining piece 16 will have a skewed form lon-

gitudinally adapting it to fit snugly to the sloping roof members with which it is associated.

Having thus fully described my said invention, what I claim as new and desire to secure by Letters Patent, is:—

1. In a car roof, the combination of a plurality of roofing sheets having marginal rebent flanges, channel plates intermediate 10 said sheets and having upstanding webs adapted for engagement with said flanges, a cap member seated on said parts, and a confining plate metal piece fitting a channel plate aforesaid and formed with a central 15 main portion, with a pair of V shape portions and with end extensions formed with orifices for the passage of fastening means, substantially as set forth.
2. In a car roof, the combination of a plurality of roofing sheets having marginal re- 20

bent flanges, channel plates intermediate said sheets and having upstanding webs adapted for engagement with said flanges, a running board, a saddle block and saddle piece associated with said running board, a 25 confining plate metal piece fitting a channel plate aforesaid and formed with a central main portion, with a pair of V shape portions and with end extensions formed with orifices for the passage of fastening means, the main portion of said piece having an upwardly deflected and orificed central portion, and a connecting bolt associated with said upwardly deflected portion and with the saddle block and saddle piece of the running 30 board, substantially as set forth.

Signed at Chicago, Illinois, this 31st day of March, 1916.

WILLIAM H. GLATTEN.
